METHOD OF PREPARING DRY CLEANING COMPOSITIONS

Martin B. Mathews, Chicago, and Charles E. Stauffer, River Forest, Ill., assignors to R. R. Street & Co., Inc., Chicago, Ill., a corporation of Illinois

No Drawing. Application October 29, 1952,
Serial No. 317,571

9 Claims. (Cl. 252—161)

Our invention relates to the cleaning or detergent field, and, more especially, the dry cleaning field, and is particularly concerned with new and improved methods of simply and directly producing compositions containing, as essential ingredients thereof, an inert high boiling organic liquid solvent having a boiling point or an initial boiling point not substantially below 200 degrees C. in which are dissolved certain oil-soluble esters of sulfopolycarboxylic acids, said compositions being substantially free of inorganic salts and, preferably, also being substantially free from water as prepared.

The compositions of matter which are prepared in accordance with our present invention are highly useful, among other purposes, as dry cleaning detergents and dry cleaning emulsifying agents and are adapted to be admixed with hydrocarbons, chlorinated hydrocarbons, and other organic solvents. They are highly effective in the production of emulsion wherein the external phase is an organic water-insoluble liquid, the internal phase being water or aqueous material or other liquids which are insoluble in the organic phase. In order to be fully effective for use in the dry cleaning field, it is important that such compositions be substantially free of inorganic salts, generally below about 0.1% by weight, and it is also highly desirable, at least in most case, that, as prepared, they be substantially free of water.

Oil-soluble esters of sulfopolycarboxylic acids are, per se, not new, being shown, for instance, in U. S. Patents Nos. 2,028,091; 2,176,423; 2,315,375 and 2,345,041. Moreover, they have heretofore been disclosed for use in dry cleaning liquid organic solvents as well as in conjunction with paraffin oils or paraffin hydrocarbons. Said esters have heretofore been prepared, for example, by reacting a maleic acid alcohol diester, for example, di-caprylmaleate, with sodium bisulfite in an aqueous medium. The resulting reaction mixture is then dried and, where it is desired that said mixture be free of inorganic salts, this has been accomplished by dissolving the reaction mixture in an organic solvent such as benzene, filtering, and evaporating the benzene. This procedure is a costly and cumbersome one in that it requires, among other things, the preliminary drying of the reaction mixture and this, in itself, presents a number of difficulties because various of the sulfopolycarboxylic acid esters are of a gummy nature and present serious problems with respect to the handling and drying thereof.

In accordance with our invention, compositions having marked efficacy in the dry cleaning field, which compositions contain an inert high boiling organic liquid solvent having a boiling point or an initial boiling point not substantially below 200 degrees C., in which are dissolved oil-soluble esters of sulfopolycarboxylic acids, are prepared in such a manner as to offer marked advantages over earlier methods heretofore suggested. As indicated, the compositions are directly prepared in a form wherein they are readily adapted for use in the dry cleaning field and form highly useful dry cleaning compositions. When added in small amounts to dry cleaning water-immiscible

2

organic solvents, such as naphtha, Stoddard solvent, carbon tetrachloride, trichlorethylene, benzene, gasoline, and the like, they enable substantial amounts of water to be taken up by the organic solvents and largely retain such water during the dry cleaning operation, the water being so finely dispersed in the organic solvent that the clarity of the latter is not visibly affected.

In the practice of our invention, the inorganic salts and moisture are removed after the reaction is essentially completed without requiring the handling of the product in the form of a solid or semi-solid gummy mass and without requiring expensive drying operations followed by extraction with organic solvents. By proceeding in accordance with our invention, these latter expensive and cumbersome steps are avoided and, at the same time, reduction of the inorganic salt content in the final product to the desired degree is readily effected in an inexpensive and simple manner.

In the practice of our invention, an alcohol ester of an unsaturated polycarboxylic acid, for example, lauryl fumarate, is reacted with an alkali bisulfite, particularly sodium bisulfite, in the presence of water and in the additional presence of an inert high boiling organic liquid solvent, for example, a petroleum hydrocarbon fraction having an initial boiling point, at atmospheric pressure, not substantially below 200 degrees C., such fraction being exemplified by a mineral oil having an initial boiling point of the order of 200 to 220 degrees C. or more. In general, we prefer to utilize petroleum fractions having a boiling point range, at atmospheric pressure, between about 200 and 400 degrees C. or, still more preferably, between about 260 and 350 degrees C. Other high boiling organic liquid solvents include esters of the type which are commonly used as plasticizers, polyglycols, etc. which are inert under the conditions of the reaction. The mixture is reacted, under conditions of agitation, at somewhat elevated temperatures, usually of the order of 95 degrees C. to somewhat in excess of 100 degrees C. until the reaction is essentially completed, that is, the production of the sulfopolycarboxylic acid ester is achieved. This usually takes at least several hours. It is preferred to carry out the reaction at atmospheric pressure but, if desired, the reaction can be performed at greater pressures in which event the reaction conditions may be somewhat modified. The mineral oil or other inert high boiling organic liquid solvent serves, among other things, to maintain the reaction mixture in a state where it can be handled as a liquid, particularly toward the end of the reaction where, if it were not present, a gummy reaction mixture would usually result which could not be stirred or satisfactorily handled.

At the completion of the reaction, there is then particularly advantageously added to the reaction mixture a further quantity of a mineral oil or similar petroleum fraction or the like having an initial boiling point not substantially below 200 degrees C. and, in addition, it is especially desirable to add a volatile organic solvent which is distillable together with water to assist in the subsequent elimination of water from the mixture. Typical examples of such latter agents are carbon tetrachloride, trichlorethylene, benzene, perchlorethylene, and toluene. The mixture is then heated to distill therefrom water and the added volatile organic solvent. In the usual case, the temperature to which the mixture is heated to effect removal of water and organic solvent will fall within the range of about 175 to about 190 degrees C. Thereafter, to the residual mass it is particularly desirable to add a petroleum fraction having an initial boiling point not substantially below 200 degrees C., for example, a mineral oil, or a volatile organic solvent such as Stoddard solvent, trichlorethylene or benzene or the like, after which the mixture is cooled and filtered. The final product is a

clear solution, substantially free of inorganic salts and of moisture, and contains a substantial proportion of the ester of a sulfopolycarboxylic acid, for example, sodium lauryl sulfosuccinate. In the usual case, we find it particularly satisfactory to produce compositions containing about 40% to about 65%, preferably about 55% to 60%, by weight, of the esters of sulfopolycarboxylic acids, in the mineral oil or like or other petroleum hydrocarbon fraction.

For particularly effective use in the dry cleaning industry, in connection with the production of oil-soluble detergents and for the formation of water-in-oil emulsions, the alcohol radical of the sulfosuccinic acid esters should be of aliphatic character and contain from 6 to about 10 carbon atoms. For other detergent and allied uses, the alcohol may be of aromatic or hydroaromatic or aromatic-aliphatic character and may contain up to 22 but preferably from 8 to 18 carbon atoms. Typical examples of such alcohols are, therefore, n-hexyl alcohol, isohexyl alcohol, n-heptyl alcohol, n-octyl alcohol, 2-ethylhexyl alcohol, mixtures of dimethyl hexanols, n-nonyl alcohol, isononyl alcohol, isomeric nonyl alcohols, decyl alcohol, undecyl alcohol, dodecyl alcohol, tetradecyl alcohol, cetyl alcohol, oleyl alcohol, stearyl alcohol, cyclohexanol, phenylethyl alcohol, benzyl alcohol, cresols, naphthols, etc. Reference may be had, for example, to the aforementioned patents for other alcohols whose esters with sulfopolycarboxylic acids are oil-soluble. It will be understood that mixtures of any two or more of such alcohols can also effectively be utilized. Those of the esters which are utilized in accordance with the present invention are, as pointed out above, the sulfopolycarboxylic acid esters in which one or all of the carboxyl groups of the polycarboxylic acid are esterified with the aforesaid alcohols. While, in the usual case, where all of the carboxyl groups of the sulfopolycarboxylic acid are esterified they will be esterified with the same alcohol or alcohols, it will be understood that the production of compositions within the scope of our invention also comprises such mixed esters wherein, for instance, one of the carboxyl groups may be esterified with, for example, one aliphatic alcohol such as hexyl alcohol, and the other or others of the carboxyl groups may be esterified with another aliphatic alcohol such as octyl alcohol.

Among the unsaturated polycarboxylic acids whose alcohol esters are utilized as one of the reactants in accordance with the present invention are, by way of example, dicarboxylic acids such as maleic acid (or maleic anhydride), fumaric acid, glutaconic acid, mesaconic acid, itaconic acid, citraconic acid, and tricarboxylic acids such as aconitic acid, and others which may be disclosed, for instance, in the aforementioned patents.

The following examples are illustrative of the practice of our invention. It will be understood that these examples are not to be construed in any way as limitative of the full scope of our invention since different alcohols can be utilized, the proportions of the ingredients can be varied, the reaction temperatures and times are likewise variable, within limits, and other modifications can be made, all within the spirit and guiding principles of the teachings herein. All parts stated are by weight.

Example 1

320 parts of dilauryl maleate, prepared by esterification of maleic anhydride with lauryl alcohol, is admixed with 30 parts of mineral oil (initial B. P. 225 degrees C.), 100 parts water and 100 parts sodium bisulfite, and the mixture is heated, with agitation, at about 98 to 100 degrees C. for about 24 hours whereby sodium dilauryl sulfosuccinate is produced in the reaction mixture. Then 90 additional parts of mineral oil and 90 parts of perchlorethylene are added and the mixture is heated and allowed to distill until the temperature of the mixture reaches about 185 degrees C. To the residual mass 110 additional parts of mineral oil is added and, after cooling

5 to room temperature or somewhat thereabove, the mixture is filtered whereupon a clear composition is obtained containing in excess of 50%, by weight, of sodium dilauryl sulfosuccinate, said composition being substantially free of inorganic salts and water.

Example 2

300 parts of dibenzyl maleate, prepared by esterification of maleic anhydride with benzyl alcohol, is admixed with 35 parts mineral oil (initial B. P. 245 degrees C.), 105 parts of water and 105 parts of sodium bisulfite, and the mixture is heated, with agitation, at about 100 degrees C. for about 20 hours. Then 90 additional parts of mineral oil and 90 parts of perchlorethylene are added and the mixture is heated and allowed to distill until the temperature of the mixture reaches 180 degrees C. To the residual mass, 100 additional parts of mineral oil is added and, after cooling to about room temperature, the mixture is filtered whereupon a clear composition is obtained containing a high percentage of sodium dibenzyl sulfosuccinate, said composition being substantially free of inorganic salts.

Example 3

200 parts of tri-n-hexyl aconitate is admixed with 16 parts mineral oil (initial B. P. 235 degrees C.), 60 parts water and 60 parts sodium bisulfite, and the mixture is heated, with agitation, at about 100 degrees C. for about 24 hours whereby sodium tri-n-hexyl sulfotricarballylate is produced in the reaction mixture. Then 50 additional parts of mineral oil and 50 parts of perchlorethylene are added and the mixture is heated and allowed to distill until the temperature of the mixture reaches about 185 degrees C. To the residual mass 65 additional parts of mineral oil is added and, after cooling to room temperature or somewhat thereabove, the mixture is filtered whereupon a clear composition is obtained containing in excess of 50%, by weight, of sodium tri-n-hexyl sulfotricarballylate, said composition being substantially free of inorganic salts.

Example 4

180 parts of trioctyl aconitate is admixed with 20 parts mineral oil (initial B. P. 245 degrees C.), 60 parts of water and 65 parts of ammonium bisulfite, and the mixture is heated, with agitation, at about 100 degrees C. for about 18 hours. Then 50 additional parts of mineral oil and 50 parts of perchlorethylene are added and the mixture is heated and allowed to distill until the temperature of the mixture reaches 180 degrees C. To the residual mass, 60 additional parts of mineral oil is added and, after cooling to about room temperature, the mixture is filtered whereupon a clear composition is obtained containing a high percentage of ammonium trioctyl sulfotricarballylate, said composition being substantially free of inorganic salts.

Example 5

200 parts of triphenylethyl aconitate is admixed with 20 parts mineral oil (initial B. P. 225 degrees C.), 60 parts water and 60 parts sodium bisulfite, and the mixture is heated, with agitation, at about 100 degrees C. for about 16 hours whereby sodium triphenylethyl sulfotricarballylate is produced in the reaction mixture. Then 50 additional parts of mineral oil and 50 parts of perchlorethylene are added and the mixture is heated and allowed to distill until the temperature of the mixture reaches about 185 degrees C. To the residual mass 60 additional parts of mineral oil is added and, after cooling to room temperature or somewhat thereabove, the mixture is filtered whereupon a clear composition is obtained containing a substantial proportion of sodium triphenylethyl sulfotricarballylate, said composition being substantially free of inorganic salts.

The proportions of ingredients utilized are subject to variation, as has been indicated above. A good working range, for instance, considered, by way of illustration, in

relation to Example 1, comprises, based on the use of 320 parts of dilauryl maleate, from about 20 to about 35 parts of mineral oil, from about 80 to about 110 parts of water, and from about 80 to about 110 parts of sodium bisulfite in the reaction proper to produce the diester of sulfosuccinic acid. A good average reaction temperature is from about 95 to about 110 degrees C. and a good average reaction time is from several hours to about 24 hours. The amount of mineral oil or the like which is added initially after the completion of said reaction is from about 70 to about 100 parts and the amount of volatile organic solvent, such as perchlorethylene, utilized will ordinarily vary from about 50 to about 150 parts. These illustrative figures will serve as guides to enable those versed in the art readily to select suitable operating conditions and proportions of ingredients effectively to carry out the teachings of our invention.

Where reference is made in the claims to the boiling point of the inert organic liquid solvent, it will be understood to include the initial boiling point of such liquids where the latter have a boiling point range as, for instance, in the case of petroleum hydrocarbons which contain mixtures of various fractions.

What we claim as new and desire to protect by Letters Patent of the United States is:

1. A method of preparing a dry cleaning composition, which comprises reacting, under agitation, an alcohol ester of a polycarboxylic acid, the alcohol radical of which contains at least 6 carbon atoms and the polycarboxylic acid radical of which contains a double bond, with an alkali bisulfite in aqueous solution and in a mineral oil having an initial boiling point not substantially below 200 degrees C., said polycarboxylic acid ester and said alkali bisulfite being present in proportions to produce the alkali salt of the sulfopolycarboxylic acid ester of said alcohol, said mineral oil being present in amounts sufficient to maintain the reaction medium in a liquid condition throughout said reaction, at the end of said reaction adding to the reaction mixture a liquid volatile organic solvent which is distillable together with water at a temperature below 190 degrees C., then heating the mixture to remove the water and at least most of the last-mentioned liquid volatile organic solvent but not said mineral oil, and filtering whereby to obtain a liquid composition substantially free of inorganic salts.

2. A method of preparing a dry cleaning composition, which comprises reacting, under agitation, an alcohol ester of a dicarboxylic acid, the aliphatic alcohol radical of which contains from 6 to about 22 carbon atoms and the dicarboxylic acid radical of which contains a double bond, with sodium bisulfite in aqueous solution and in a mineral oil having a boiling point between about 260 and 350 degrees C., said dicarboxylic acid ester and said

sodium bisulfite being present in proportions to produce the sodium salt of the sulfodicarboxylic acid ester of said alcohol, said mineral oil being present in amounts sufficient to maintain the reaction medium in a liquid condition throughout said reaction, at the end of said reaction adding to the reaction mixture a mineral oil having a boiling point between about 260 and 350 degrees C. and also adding a liquid volatile organic solvent which is distillable together with water at a temperature below 190 degrees C., then heating the mixture to remove the water and at least most of the last-mentioned liquid volatile organic solvent but not said mineral oil, and filtering whereby to obtain a liquid composition substantially free of inorganic salts.

- 15 3. A method of preparing a dry cleaning composition, which comprises reacting, under agitation, an alcohol ester of a tricarboxylic acid, the alcohol radical of which contains from 6 to about 22 carbon atoms and the tricarboxylic acid radical of which contains a double bond, with an alkali bisulfite in aqueous solution and in a mineral oil having an initial boiling point not substantially below 200 degrees C., said tricarboxylic acid ester and said alkali bisulfite being present in proportions to produce the alkali salt of the sulfotricarboxylic acid ester of said alcohol, said mineral oil being present in amounts sufficient to maintain the reaction medium in a liquid condition throughout said reaction, at the end of said reaction adding to the reaction mixture a liquid volatile organic solvent which is distillable together with water at a temperature below 190 degrees C., then heating the mixture to remove the water and at least most of the last-mentioned liquid volatile organic solvent but not said mineral oil, cooling the residual product, and then filtering whereby to obtain a liquid composition substantially free of inorganic salts and water.
- 20 4. A method in accordance with claim 1, wherein the alcohol is phenylethyl alcohol.
- 25 5. A method in accordance with claim 3, wherein the alcohol is oleyl alcohol.
- 30 6. A method in accordance with claim 3, wherein the tricarboxylic acid is aconitic acid.
- 35 7. A method in accordance with claim 6, wherein the alcohol is tetradecyl alcohol.
- 40 8. A method in accordance with claim 6, wherein the alcohol is lauryl alcohol.
- 45 9. A method in accordance with claim 6, wherein the alcohol is cetyl alcohol.
